UNITED STATES PATENT OFFICE.

AMOS L. KNIGHT AND WILLIAM N. CLEMENTS, OF PHILADELPHIA, PENNSYLVANIA,
ASSIGNORS TO LANSTON MONOTYPE MACHINE COMPANY, OF PHILADELPHIA,
PENNSYLVANIA, A CORPORATION OF VIRGINIA.

TYPE-MOLD.

1,024,512.

Specification of Letters Patent. Patented Apr. 30, 1912.

Application filed December 11, 1911. Serial No. 665,005.

To all whom it may concern:

Be it known that we, AMOS L. KNIGHT and WILLIAM N. CLEMENTS, citizens of the United States, and residing at Philadelphia, 5 in the county of Philadelphia and State of Pennsylvania, have invented certain new and useful Improvements in Type-Molds; and we do hereby declare the following to be a full, clear, and exact description of the 10 same, reference being had to the accompanying drawings, forming part of this specification, and to the figures and letters of reference marked thereon.

This invention relates to the manufacture of what are known as short body type, the latter possessing all the characteristics of ordinary printing type save as to the length of body, which latter is materially shortened, and the addition of means for 20 effecting their retention in specially prepared forms or holders for application to addressing and similar machines; and it has for its principal object the production of a mold, specially contrived and adapted 25 for use in commercial automatic type casting and composing machines, by means of which said type can be rapidly, accurately and economically produced, and, if desired, set up in justified lines ready for application to the form or holder with which they 30 are designed to be associated.

To these ends the invention consists in the construction, combination and arrangement of parts constituting or forming elements of 35 the type mold hereinafter fully described, the novel features whereof are specifically pointed out in the appended claims.

In the accompanying drawings, illustrating a preferred form of embodiment of 40 said invention,—Figure 1 is a top plan view of the mold; Fig. 2 is a similar view with side blocks, mold blade and mold plate omitted; Fig. 3 is a right hand end view; Fig. 4 is a vertical section in the plane of 45 one side of the mold blade; Fig. 5 is a partial vertical section through the cross block near the end of nick pin; Fig. 6 is a perspective of the two side blocks detached; Fig. 7 is a perspective of the floor plate; Fig. 8 is a perspective of the mold plate; 50 Fig. 9 is a perspective of the two base sections of the cross block; Fig. 10 is a side elevation, and Fig. 11 an end view of the

mold blade; Fig. 12 is a perspective of the jet ejector; Fig. 13 is a perspective of the 55 bottom nick pin; Fig. 14 is a perspective of the produced type.

The same numerals designate like parts in the several figures.

The type, Fig. 14, which the mold illustrated is designed to produce, comprises a head or character 1 accurately formed in justified relation upon one end of the short rectangular body 2, the opposite sides whereof, corresponding with the top and bottom 65 of the character, contain retaining grooves or channels 3, while the base or foot is recessed part way across from one side, as at 4, to furnish a means for determining the set of the character or its position in the 70 line when assembled, said one side bottom recess serving as a substitute for the usual indicating nick whose function in this respect is nullified by the presence of the opposed retaining groove.

The mold is specially designed for use in automatic casting and composing machines of the type indicated in Patent No. 625,998, dated May 30, 1899, and is provided with the usual base plate 5, front abutment 6 80 carrying adjustable shoe 7, and squaring plate 8 adjustably attached to base 5 parallel with front abutment 6. In the angle between squaring plate 8 and base 5 and detachably secured to each of said members 85 is a right angled or L-shaped floor plate 9, the upper faces 9^a and 9^b of the body and vertical members whereof lie in parallel planes at right angles to the inner and outer faces 9^c 9^d of the vertical member of said 90 floor plate. In the way or channel between squaring plate 8 and the angular extension or vertical member of floor plate 9 are seated and secured two guide blocks 10, 11 95 spaced apart by an interposed point block 12 upon which they are clamped by a through bolt 13. Bolts 8^x passing through enlarged orifices in the squaring plate 8 and threaded into blocks 10, 11 and bolts 9^x passing through enlarged orifices in said 100 blocks and threaded into the floor plate serve to retain said blocks firmly in adjusted position. Each of said blocks 10, 11 is formed or provided at one edge with an extension or plate 14 overlying and seating 105 upon the upper face 9^b of the angular exten-

sion of floor plate 9. The width of the extension 14 is somewhat in excess of that of face 9^b and overhangs or projects beyond the inner vertical face 9^c while the proximate edges or faces of said extensions 14 are in parallel planes perpendicular to face 9^b and of a thickness corresponding to the height of the body of the type to be produced. In the example illustrated and for 10 the purpose of producing side grooves 3 the opposing faces of extensions 14 are each provided with a rib or projection 15 preferably produced by slotting the face longitudinally and inserting a filling piece 16, 15 the latter projecting beyond the face of extension 14 and held in position by a tapered pin 17 or equivalent fastening device, inserted from below so as to be held from displacement by the contacting face of the 20 floor plate.

The squaring plate 8 is notched or cut away, as at 18, opposite the channel between guide blocks 10, 11 and is provided with an outside bearing 19 for the 25 outer end of the mold blade carrier 20, the latter fitted to slide between the proximate faces of blocks 10, 11 and provided at its inner upper corner with the mold blade 21 filling the space between the proximate 30 edges of extensions 14 and serving both as the variable dimensioning member for the mold cavity and a means for ejecting the type therefrom; in other words, the cross section of the mold blade corresponds with 35 the space or channel between extensions 14 and face 9^b, its sides being grooved, as at 22, to fit ribs 15 and the under surface grooved as at 23 to fit the nick pin 24. This nick pin, so called, is preferably in the 40 form of a cylinder inserted in a hole drilled from the face 9^c parallel with and partially intersecting face 9^b of the vertical member of the floor plate, the inner end of said pin terminating short of the inner edges of extensions 14, overhanging the inner face 9^c, and having the lower section of the overhanging end cut away, as at 25, in the plane of face 9^b. The nick pin 24 is retained 45 against longitudinal displacement by a key 50 26 located in a transverse groove 27 in floor plate 9.

Mounted to reciprocate longitudinally in the way or channel between floor plate 9 and front abutment 6 is the cross block 28 55 forming the removable side of the mold cavity and containing the jet or sprue opening through which molten metal is conducted to the bottom of the mold cavity, the latter bounded on the sides by extensions 14, mold 60 blade 21 and mold plate 29. The mold plate 29, corresponding in thickness with extensions 14 and engaging the inner edges of the latter when in casting position, is detachably secured to two L-shaped base sections 30, the latter spaced to form the jet

opening next floor plate 9 and a guide for the movable jet ejector blade 31, the last named engaging a cam plate 32 fixed to base plate 5. The lower sections or limbs of base sections 30 are extended beneath front abutment 6 while the upper sections or stems project on the opposite side beneath extensions 14, and in the angle between the two limbs of the base sections is seated the squaring plate 33 engaging shoe 7. Mold plate 29 70 and squaring plate 33 are each securely fastened to base sections 30 by bolts 34, 35, and by arranging the squaring plate in the angular seat at the junction of the two limbs of the base sections, the rigidity and initial 80 adjustment of the associated elements forming the cross block is greatly promoted.

It should be noted that when the cross block is in casting position, as indicated in Fig. 4, the top surfaces of the mold plate, 85 mold blade and extensions 14 are in the same plane and form a seat for the reception of the matrix, of which latter a large number are carried in the die-case (not shown) for selective presentation to the 90 mold; that the gate or passage in the cross-block is in register at the top with the opening or space around the overhanging end of the nick pin at the bottom of the mold cavity and at the bottom with the jet opening 95 36 of the nozzle seat in the base plate 5; and that at this period the jet ejector blade 31 stands retracted or withdrawn from floor plate 9, thereby opening the gate for the passage of metal from the jet opening 100 around the nick pin into the mold cavity. After the cast is made the cross-block is moved to uncover the side of the mold cavity and sever the jet from the type, the 105 ejector blade is advanced to discharge the jet, and a type carrier, (not shown) is presented to receive the type as discharged from the mold by the mold blade, after which the type carrier and cross-block are shifted again, the one to transfer the contained type to the assembling devices or 110 deliver it to a suitable receptacle, and the other to close the side of the mold preliminary to the adjustment of the mold blade for set, and the application of the matrix 115 for character.

The mold blade carrier is recessed for the reception of the point block and is held down upon its seat on the floor plate and bearing 19 by a top guide 37 detachably secured to block 10 and engaging the upper edge of said carrier.

To facilitate the setting of the injected metal within the mold and to reduce the tendency to distortion incident to expansion, 125 the floor plate is provided with a water circulation specially designed to reach and act upon the vertical member thereof in proximity to the mold cavity and to react upon the applied extensions 14, mold blade and 130

- mold plate. With these ends in view, the lower or horizontal member of the floor plate is provided with longitudinal internal passage 39 near its inner edge and the vertical extension or member of said floor plate is also provided with a like passage 40 near its upper edge in proximity to the face 9^b for the reception of the block extensions 14. Corresponding ends of passages 39, 40 are united through a branch 41 and the opposite end of each is connected by a branch 42 or 43 with a port 44 or 44^x adapted to register with a similar port in the base plate for the admission and discharge of a cooling agent, such as water.
- Owing to its motion and concealed position difficulty has been experienced in insuring and maintaining proper lubrication of the jet ejector in the cross-block, and to overcome this the following construction has been devised. The proximate faces of the two base sections in contact with the jet ejector are each furnished with a groove 45, preferably diagonally disposed relatively to the line of motion of the ejector blade and extending transversely thereof, and one of said sections is provided with an oil receptacle 46 communicating through a passage 47 with a groove or duct 48 located to one side of groove 45. The ejector blade is furnished with a notch or opening 49 adapted to register alternately with duct 48 and grooves 45. The arrangement is such that when the ejector blade is in its retracted position, to permit the cast to be made, opening 49 will register with duct 48 and receive a supply of oil therefrom, and when the blade is reciprocated, to eject the jet, opening 49 will be brought into register with grooves 45 so as to permit the contained supply to flow into said grooves.
- The mold as a whole is designed and adapted for use in the type casting machines hereinbefore referred to as a substitute for the full body mold previously employed, but when employed for setting up composed matter the type assembling devices should be modified to correspond with the reduced dimensions of the produced type bodies.
- Having thus described our invention, what we claim as new and desire to secure by Letters Patent of the United States, is:—
1. In a type mold provided with a base plate, front abutment and squaring plate and in combination therewith a floor plate provided with a vertical extension along its inner margin, two guide blocks mounted upon the floor plate between its vertical extension or limb and the squaring plate, said blocks spaced to form a channel and each provided with an off-set extension overlying and projecting beyond the vertical extension of the floor plate; a movable cross-block engaging said floor plate and provided with a mold plate engaging the extensions of the guide block, and a mold blade movable within the channel between the guide block extensions and provided with a carrier located between the guide blocks.
  2. A short body type mold for type casting and composing machines provided with a mold cavity opposing sides whereof are equipped with parallel ribs adapted to form side grooves in the produced type, a partial closure for the base of said cavity provided with an inwardly projecting rib to form a nick in the base of the type, said nick extending part-way across the latter, a movable mold plate forming one wall of said cavity, and an opposing movable mold blade constituting the fourth side wall of said cavity and grooved on the sides and bottom to fit the aforesaid side and bottom ribs.
  3. A short body type mold for type casting machines provided with a base plate containing a jet opening, a front abutment and a squaring plate, and in combination therewith, an L-shaped floor plate secured to the base and squaring plates with its vertical limb remote from and parallel with said squaring plate; two guide blocks secured in the angle between the horizontal and vertical limbs of the floor plate and each provided with an offset extension or flange overlying and projecting beyond the top face of the vertical limb of said floor plate, said blocks being spaced to form a guiding channel; a movable mold blade located between the proximate edges of the guide block extensions and engaging the upper face of the floor block extension; a carrier for said mold blade guided in the channel between the guide blocks; and a movable cross-block interposed between the front abutment and floor plate provided with a base extending beneath the overhanging edges of the guide block extensions and containing a jet passage, and a mold plate engaging the edges of said guide block extensions.
  4. A short body type mold provided with a mold cavity, two opposed side walls whereof are equipped with inwardly projecting parallel ribs, to form side grooves in the produced type, a nick-forming inwardly projecting rib parallel with said first mentioned ribs and partially closing one end of said cavity, a movable mold blade interposed between said side walls and grooved to fit upon said ribs, a movable mold plate opposed to the mold blade and constituting a fourth or removable side wall of said cavity, and a cross block movable beneath said cavity and provided with a jet opening adapted in one position of adjustment to register with the end of said cavity.
  5. A short body mold for type casting and composing machines provided with a mold cavity formed by relatively adjustable opposed side walls in parallel relation and each equipped with an inwardly projecting

rib, a movable mold blade and an opposed movable mold plate, a nick pin parallel with said ribs and partially closing the end of said mold cavity, a mold blade fitting and 5 movable longitudinally of said ribs and pin to vary the setwise dimensions of the produced type and discharge the same from the mold cavity, and a member movable transversely of said mold cavity beneath the nick 10 pin and containing a jet opening or passage through which molten metal is conducted into the end of the mold cavity around the nick pin.

6. A type mold provided with a molding 15 cavity the side walls whereof are formed by opposed fixed side blocks, a movable mold plate and an opposed movable mold blade, a floor plate provided with a nick pin, and a cross block movable beneath said pin and 20 containing a jet passage.

7. A type mold provided with a molding cavity comprising a floor plate, fixed side blocks extending beyond the margin of the floor plate, a movable mold blade intermediate the side blocks and overlying the 25 floor plate, a nick pin located in the face of the floor plate intermediate the side blocks and extending beyond the margin of said floor plate to a less extent than the side 30 blocks, a movable cross block engaging the margin of the floor plate and extending beneath the overhanging portions of the side blocks and nick pin, said cross block provided with a jet passage and a mold plate, 35 the latter engaging the edges of the overhanging portion of the side blocks.

8. In a type mold provided with an L-shaped floor plate, flanged side blocks, a movable mold blade and a movable cross 40 block, the latter equipped with a jet passage, jet ejector and mold plate and in combination therewith, a nick pin mounted on the floor plate and projecting beyond the edge thereof above the cross block.

45 9. In a type mold provided with a floor plate, side blocks mounted upon and extending beyond the margin of said floor plate, a movable mold blade and a movable cross block, the latter engaging the floor plate and 50 provided with a jet passage located beneath the overhanging edges of the side blocks and with a mold plate engaging the edges of the said blocks, and in combination there-

with, a nick pin mounted on the floor plate and projecting above the cross block in the 55 interval between the side blocks.

10. A type mold provided with an L-shaped floor plate containing communicating internal cooling passages or ducts extending longitudinally of its upright member 60 near the top and bottom margins thereof, and with opposite ends communicating the one with an inlet and the other with an outlet port, flanged side blocks mounted in the angle between the members of the floor 65 plate with their flanges overlapping the upright member of said floor plate, and a mold blade overlying the upright member of the floor plate and attached to a carrier engaging the horizontal member of the floor plate 70 and guided thereon by the side blocks.

11. A type mold provided with a floor plate provided with two members in angular relation, flanged side blocks seated and secured in the angle of the floor plate with their 75 flanges overlying one of the members thereof, a point block interposed between said side blocks, means for clamping the side blocks upon said point block, and a mold blade interposed between the flanges of and 80 its carrier guided between the side blocks.

12. In a type mold, a cross block comprising two right angle base sections spaced to form a jet opening or passage, a movable jet 85 ejector in said passage, a mold plate secured to the upright members of said angular base sections, and a squaring plate seated in the angle between the limbs of the base sections and secured to both limbs of said sections to 90 form a rigid structure.

13. In a type mold, a cross block provided with a movable ejector blade guided in a way therein, distributing channels in the walls of said way, a transverse opening in 95 said ejector blade, and a port in one wall of said way communicating with an oil supply, the arrangement being such that in one position of the ejector the opening therein will register with said port and in another position with the distributing channels.
